Primary Examiner — Jonathan J Han(74) Attorney, Agent, or Firm — Banner & Witcoff, Ltd.CLAIM

The ornamental design for a shoe, as shown and described.

DESCRIPTION

FIG. 1 is a rear perspective view of a shoe showing my new design;

FIG. 2 is a side view thereof;

FIG. 3 is a rear view thereof;

FIG. 4 is an opposite side view thereof; and,

FIG. 5 is an opposite side rear perspective view thereof. The even-length broken lines represent stitching. The uneven-length broken line rectangular shape within the shaded area forms no part of the claimed design. The uneven-length broken lines depicting the remainder of the shoe form no part of the claimed design.
